UNITED STATES PATENT OFFICE.

JAMES J. BROGAN, OF HIGHTSTOWN, NEW JERSEY, ASSIGNOR TO CROMPTON & KNOWLES LOOM WORKS, OF WORCESTER, MASSACHUSETTS, A CORPORATION OF MASSACHUSETTS.

TUBE-FRAME CLUTCH.

Application filed June 25, 1924. Serial No. 722,413.

This invention relates to Axminster looms and more particularly to an improved clutch which cooperates with the means for stopping such looms when the tube frames carrying the portable supply of yarn fails to move to weaving position.

In looms of the type to which this invention relates there is usually provided a series of tube frames which are presented successively to operative position, each tube frame being withdrawn from the series and moved to weaving position to permit the formation of tufts and then returned to the series. It occasionally happens that the devices for releasing the tube frames do not operate properly and they will remain in raised position. Under such conditions it is desirable to stop the loom to prevent the formation of an empty row across the fabric.

20 Looms of the type referred to usually employ several hundred tube frames which are likely to vary slightly in length and it is desirable that the stop motion be independent of these variations.

25 The stop motion shown in Patent No. 1,546,685 provides an adjustable screw in each clutch to engage a projection on the tube frame whenever the latter is not properly released. The screw has the same setting for all the tube frames, and cannot operate properly with a tube frame slightly under size. Moreover, the screw is provided primarily for the purpose of releasing the frames from their transporting chains, and the stopping of the loom is a secondary matter.

In order to provide for more certain operation of the stop motion I have provided each clutch with a yielding device which operates with the stopping mechanism independently of the screw and slight variations in the length of the tube frames.

A more particular object of my invention is to provide the clutch with a yielding plunger associated with an adjustable tube frame spring releasing device wherein the yielding plunger, which is made to cooperate with the stop motion, operates independently of the varying adjustable positions of the device.

With these and other objects in view which will appear as the description proceeds, my invention resides in the combination and arrangement of parts hereinafter described and set forth in the claims:

In the accompanying drawing, wherein one form of my invention is shown,

Fig. 1 is a side elevation of a portion of an Axminster loom having my invention applied thereto,

60 Fig. 2 is an enlarged rear elevation of the clutch mechanism looking in the direction of arrow 2, Fig. 1, and

Fig. 3 is an enlarged section on line 3—3 of Fig. 1, looking in the direction of the 65 arrows.

Referring more particularly to the drawing it will be seen that I have provided a loom frame 10 having bearings 11, one of which is shown in the drawing, to receive 70 cross shaft 12 on which is mounted a pair of arms, one of which is indicated at 13, Fig. 1. The arms are raised and lowered by means of a connector 14 which is operated from an appropriate part (not shown) of 75 the loom and there is pivoted on each arm 13 for motion in a substantially horizontal plane, a clutch carrying lever 15 which moves about stud 16 carried by arm 13. By means of mechanism similar to that shown in Patent No. 1,86,374, lever 15 is moved toward the tube frame when in raised position as indicated in full lines in Fig. 1, the result of which is to present clutch 17 to the tube frame to release the same so it may be moved 80 with the arm to weaving position as indicated in the dotted line position. In the process of weaving it is necessary to rock the tube frame so that the tufts of yarn may be properly placed. This is accomplished by 85 pivoting clutch 17 to the adjacent arm 15 as at 18 and providing each clutch with a connector 19 pivotally connected to the clutch by stud 20.

A cam plate 21 rotates with shaft 22 and 90 carries a cam patch 23 positioned for engagement with the rear end 24 of a lever 25 pivoted to a fixed stud 26. The upper arm 27 of lever 25 has pivoted thereto as at 28 a floating lever 29, the rear end of which is connected to the lower end of depressor rod 30, the upper end of which is received in fixed guide 31 and positioned in the path of arm 13. The forward end of lever 29 is provided with a notch 32 which cooperates 100 with lever 33 to stop the loom whenever depressor rod 30 remains in raised position because of the failure of arm 13 to depress the same. The matter thus far described is in common use and for a more complete de- 110

scription thereof reference may be had to the aforesaid Patent No. 186,374 and Patent No. 1,546,658.

My invention has more particular reference to the clutch as shown in Figs. 2 and 3. The stud 20 is provided with an enlarged integral hexagonal head 40 and a threaded shank 41 which extends through the upper part of the clutch 17. The stud 20 is adjustable longitudinally so that the threaded end thereof may extend beyond the inner face 42 of the clutch 17 and be held in such adjusted position by means of lock nut 43. The threaded shank 41 passes through a guide 44 which is held against the head 40 by means of lock nut 45 and has the lower end thereof perforated to receive the outer end of a plunger 46. The latter is formed with a head 47, by means of which the enlarged 10 rectangular end 48 of the plunger may be moved toward the tube frame by means of compression spring 49 which lies between the guide 44 and the head 47. The head 47 engages the clutch and limits motion of the 15 plunger under action of the spring.

The invention may be used in connection with a tube frame such as shown in Fig. 3 having a tubular portion 50, a spool bearing bracket 51, a spool 52, and a chain engaging spring 53 held to the tube frame by means of screw 54. The parts are so proportioned that when the tube frame assumes the 20 position shown in dotted lines in Fig. 3 the plunger will have been depressed by the tube frame and will lie over screw 54.

In the normal operation of the loom the clutches will be moved toward the adjacent ends of the tube frames to cause the latter to move upwardly on cam face 55 of the 25 clutch. The projecting end 48 of the plunger will be depressed by the spring 53 against the action of spring 49. When the parts have been properly placed, the mechanism operating upon connector 14 will move 30 to permit arms 13 to fall and if the tube frame is properly released it will move to weaving position and arm 13 will depress the rod 30 so that as the floating lever 29 moves forward, it will not engage rocking 35 lever 33. However, should the tube frame fail to be released, the head 48 of the plunger 46 will engage the screw 54 and the clutch 17 and arm 13 will be held in raised position so that as lever 29 moves forwardly the 40 front end thereof will be in lower position and engage lever 33 to rock the same to cause the stopping of the loom.

It will be seen from the foregoing that even though the successive tube frames are 45 of slightly varying lengths the plunger 46 will nevertheless engage screw 54, the amount by which the head 48 extends beyond the face 42 being sufficient to accommodate all ordinary variations in the lengths of the 50 tube frames. It will also be noted that al-

though stud 20 is adjustable lengthwise in the clutch yet the guide 44 will always be in position not only to receive the plunger but also to serve as an abutment for spring 49.

Having thus described my invention it will be apparent that changes and modifications may be made therein without departing from the spirit and scope of the invention, and I do not wish to be limited to the details 75 herein disclosed but what I claim is:

1. A clutch for Axminster looms operating with a series of yarn tube frames movable one by one to operative position and each having a projection extending therefrom and a disconnecting member attached thereto, said clutch having a stud longitudinally adjustable thereon to engage the disconnecting member and a yielding plunger to lie vertically above the projection when the clutch 80 and tube frame are in engagement with each other.

2. A clutch for Axminster looms operating with a series of yarn tube frames movable one by one to operative position and each having a projection extending therefrom and a disconnecting member carried thereby, said clutch having a stud thereon adjustable toward and from the tube frame in operative position to engage the member, said clutch 85 having a plunger yieldingly movable with respect thereto and movable substantially parallel to the stud and positioned for engagement with the disconnecting member vertically above the projection.

3. A clutch for Axminster looms operating with a series of yarn tube frames movable one by one to operative position and each having a projection extending therefrom and a disconnecting spring thereon, said clutch having a stud thereon adjustable toward and from the disconnecting spring and positioned for engagement therewith, a plunger yieldingly mounted on the clutch and positioned to engage the disconnecting spring 100 above the projection, and a guide for said plunger carried by the stud and holding said plunger in operative position for all adjusted positions of said stud.

4. In an Axminster loom having a tube frame with a projection thereon and a hook member on the frame to support the same, a clutch for the tube frame to engage the hook member and move the same to a position to release the tube frame and having a 115 downward movement to carry the frame to weaving position, and a yielding plunger on the clutch to lie over the projection when the clutch is in position to move the tube frame to weaving position, said plunger engaging the projection when the tube frame is held from moving to weaving position to prevent the downward movement of the clutch.

5. A clutch for Axminster looms operating 120

with a series of yarn tube frames each having a disconnecting member attached thereto by means which extend beyond the vertical plane of the member, said clutch having a 5 stud thereon to engage the disconnecting member and having also a yielding plunger adapted to engage the member and positioned when the clutch is operatively related to a tube frame to lie vertically over 10 the means.

6. A clutch for Axminster looms operating with a series of yarn tube frames each having a projection extending therefrom and each having a disconnecting member attached thereto, said clutch having a stud longitudinally adjustable thereon to engage the disconnecting member, said clutch also having a plunger slideable thereon substantially parallel to the stud, and yielding 15 means interposed between the stud and the plunger to hold the latter vertically above 20

the projection of a tube frame which is in operative engagement with the clutch in all adjusted positions of the stud.

7. In a clutch for Axminster looms operating with a series of yarn tube frames movable one by one to operative position and each having a disconnecting member attached thereto and a projection extending therefrom, said clutch having a stud therein 25 to engage the disconnecting member, and a plunger extending substantially parallel to the stud, a guide for the plunger supported by the stud, and resilient means between the guide and the plunger to hold the same vertically above the projection of a tube frame which is operatively in engagement with the clutch. 30

In testimony whereof I have hereunto affixed my signature.

JAMES J. BROGAN.
